UNITED STATES PATENT OFFICE

FREDERIK CARL CHRISTIAN VOGEL, OF HAMBURG, GERMANY, ASSIGNOR TO THE FIRM
VOGEL & HALKE, OF HAMBURG, GERMANY

DESIGN FOR A SCALE CASING

Application filed May 28, 1928. Serial No. 26,895. Term of patent 14 years.

To all whom it may concern:

Be it known that I, FREDERIK CARL CHRISTIAN VOGEL, a citizen of Germany, residing at Hamburg, Germany, Konigstrasse 14-16, have invented a new, original and ornamental Design for a Scale Casing, of which the following is a specification, reference being had to the accompanying drawing, forming part thereof.

Fig. 1 is a plan view, Fig. 2 is a side elevation, and Fig. 3 is a front elevation of the scale casing, showing my new design.

I claim:

The ornamental design for a scale casing, as shown.

FREDERIK CARL CHRISTIAN VOGEL.
